DESIGN FOR A TAIL LAMP FOR VEHICLES

Le Roy O. Brown, Chicago, Ill., assignor to Just-rite Manufacturing Company, Chicago, Ill., a corporation of Illinois

Application June 17, 1935, Serial No. 57,294

Term of patent 7 years

To all whom it may concern:

Be it known that I, Le Roy O. Brown, a citizen of the United States and a resident of Chicago, in the county of Cook and State of Illinois, have invented a new, original, and ornamental Design for a Tail Lamp for Vehicles, of which the following is a specification, reference being had to the accompanying drawing, forming a part hereof, wherein

Fig. 1 is a front elevation of a tail lamp for vehicles embodying my design.

Fig. 2 is a side elevation of the same.

Fig. 3 is a rear elevation of the same.

I claim:

The ornamental design for a tail lamp for vehicles as shown.

LE ROY O. BROWN.
